Primary Examiner—James Gandy*Assistant Examiner*—Cathron B. Matta*Attorney, Agent, or Firm*—Richard B. O'Planick; Timothy A. Nathan[57] **CLAIM**

The ornamental design for a bottle collar, as shown and described.

DESCRIPTION

FIG. 1 is a top right front perspective view of a bottle collar showing my new design;

FIG. 2 is a top plan view thereof;

FIG. 3 is a front elevational view thereof; the rear elevational view being a mirror image;

FIG. 4 is a right side elevational view thereof; the left side elevational view being a mirror image;

FIG. 5 is a bottom plan view thereof; and,

FIG. 6 is a top right front perspective view showing the bottle collar as it would appear on a bottle. The broken line showing of a bottle is for illustrative purposes only and form no part of the claimed design.
